UNITED STATES PATENT OFFICE.

JOHN G. RAHNER, OF LEBANON, ILLINOIS, ASSIGNOR OF ONE-HALF TO
CHRISTIAN J. PFEFFER, OF SAME PLACE.

WHIP ATTACHMENT FOR HOLDING RIBBONS, BANNERS, &c.

SPECIFICATION forming part of Letters Patent No. 394,509, dated December 11, 1888.

Application filed July 27, 1888. Serial No. 281,193. (No model.)

To all whom it may concern:

Be it known that I, JOHN G. RAHNER, of Lebanon, in the county of St. Clair and State of Illinois, have invented a certain new and useful Improvement in Whip Attachments for Holding Ribbons, Banners, &c., of which the following is a full, clear, and exact description, reference being had to the accompanying drawings, forming part of this specification.

This invention relates to devices for attaching marriage or campaign favors, &c., to whip-stocks, &c.; and the invention consists in features of novelty hereinafter fully described, and pointed out in the claims.

Figure I is a detail perspective of a whip-stock with my attachment devices secured thereto. Fig. II is an enlarged perspective view of my spring-clasp that grasps the stock and its triplicate forks for holding the ribbons or favors, and Fig. III is an enlarged section of the spiral spring-ring that is seated around the spring-clasp shown in Fig. II to re-enforce the hold of the same and as a means for attachment of banners, &c.

Referring to the drawings, in which similar figures of reference indicate like parts in all the views, 1 represents a whip-stock.

2 is a spring-clasp whose open ring 3 clutches around the whip-stock, and which is provided with triplicate forks 4, which are elastically connected to said open ring by bow-strings 5, that are integral therewith. The three forks are preferably rounded at top and curved slightly outward, so as to facilitate the passage of the ribbon or favor 6 over or between the same. I have shown and described triplicate forks; but do not confine myself to that number, for the same may be increased or diminished without departing from the essential features of this invention.

7 represents a spiral spring-ring which fits around, is seated on, and re-enforces the attachment of the open ring of the spring-clasp on the whip-stock that it embraces, and 8 are banners or bannerets whose staffs may be passed through the spirals of the spiral spring-ring, and may thus, as are the ribbons, be used as marriage or campaign favors, or as

memorials of rejoicing, &c. The use of the 50 spiral spring-ring around the open ring of the triplicate fork-clasp makes the attachment to the whip-stock much more secure, adds to the elegance of the device, and also provides it with additional facilities for the insertion and 55 attachment of the favors and bannerets to be secured to the whip-stocks. These favors are largely in use in some cities for other than marriage or campaign purposes—such, for instance, as distinguishing the whips and turn-outs of different livery establishments, the name of the establishment and its proprietor being printed or emblazoned on the ribbons or bannerets. Thus, also, when used as wedding favors the names of the two families to 60 be united may be portrayed, or when as campaign favors the names of the candidates.

I do not confine myself to the especial arrangement of the favors shown in Fig. I, for the ribbons, bannerets, &c., can be inserted 70 in various positions, loops, or angles to suit the taste of the party using the whip.

The spring-clasp 2, constructed of the open ring 3, bows 5, and triplicate forks 4, is made of any suitable elastic material, so that the 75 open ring will expand to the size of its seat on the whip-stock and spring to its grasp of the same.

9 represents a ring, of brass or other suitable material, located within the spirals of the 80 spiral ring 7, and whose function is to limit the expansion of said spiral spring-ring, so that it can not be slid down too far on the whip-stock, &c.

The spiral spring-ring may be made of 85 brass wire or any other suitable material that will re-enforce the spring-clasp of the open ring.

The same attachment devices may be used for securing ribbons and other favors to flag 90 and banner staffs, &c.

I claim as my invention—

1. In an attachment for whips, &c., the spring open ring-clasp 3, arranged to embrace the whip-stock, the spring-bows that surmount 95 the open ring, and forks that surmount the bows, substantially as and for the purpose set forth.

2. In an attachment for whips, &c., the spring open ring-clasp 3, spring-bows 5, forks 4, and spiral spring-ring 7, substantially as and for the purpose set forth.
- 5 3. In an attachment for whips, &c., the spring open ring-clasp 3, spring-bows 5, forks 4, spiral spring-ring 7, and the ring 9 within the spiral ring that limits its expansion, substantially as and for the purpose set forth.

JOHN G. RAHNER.

In presence of—

BENJN. A. KNIGHT,
SAML. KNIGHT.
